UNITED STATES PATENT OFFICE.

JACOB LADER, OF NEW YORK, N. Y., ASSIGNOR TO ATLAS & BLUHM, OF NEW YORK,
N. Y., A CORPORATION OF NEW YORK.

DESIGN FOR A PRINTED FABRIC.

Application filed July 22, 1925. Serial No. 14,175. Term of patent $3\frac{1}{2}$ years.

To all whom it may concern:

Be it known that I, JACOB LADER, a citizen of the United States, and a resident of the city of New York, borough of Manhattan, in the county of New York and State of New York, have invented a new, original, and ornamental Design for a Printed Fabric, of which the following is a specification.

Reference is to be had to the accompanying drawing in which the figure illustrates a swatch of material with my new design printed thereon.

I claim—

The ornamental design for a printed fabric as shown.

JACOB LADER.
